UNITED STATES PATENT OFFICE.

FREDERICK REUTER, OF BROOKLYN, NEW YORK, ASSIGNOR TO JOHN C. GRAHAM, OF PHILADELPHIA, PENNSYLVANIA.

DESIGN FOR FRINGE.

SPECIFICATION forming part of Design No. 13,097, dated July 25, 1882.

Application filed June 16, 1882. Term of patent 14 years.

To all whom it may concern:

Be it known that I, FREDERICK REUTER, of Brooklyn, in the county of Kings and State of New York, have invented and produced a new and original Design for Fringe, of which design the following is a specification.

The accompanying drawing is a side view of a section of fringe embodying and illustrating my design, which consists in a fringe having a heading, A, to which is attached a series of chenille pendants, B, ornamented by the following arrangement of colors in the threads of which they are composed, to wit: A portion, *b*—say about one-half of the length of the pendant—is formed of threads of a single color, but graduated, shaded, or tinted so as to gradually vary in depth or intensity from one end to

the other of the portion *b*. The remainder of the pendant is made up of a series of stripes, belts, or bands, *b'*, of two or more different colors, said series of stripes presenting the appearance or effect of a variegated border or frieze upon the fringe.

I claim—

A design for fringe, consisting of pendants which for a portion of their length are of a single color, graduated or shaded in depth, and for the remainder are striped, belted, or banded in two or more colors, substantially as set forth.

FREDERICK REUTER.
